INCENDIARY PROJECTILE

Clarence W. Galen, Battle Creek, Mich., assignor
to The Duplex Printing Press Company, Battle
Creek, Mich., a corporation of Michigan

Application October 23, 1941, Serial No. 416,271

11 Claims. (Cl. 102—90)

1

This invention is a novel improvement in projectiles, and one object thereof is to provide a novel projectile containing an oxygen releasing substance, said projectile being so constructed and designed that upon impact against objects, same will burn its way therethrough, spraying hot molten metal upon partial penetration thereof and causing severe concussion particularly in event the sprayed molten metal should come in contact with oil such as derived from broken oil tanks or bunkers, or with oil derived from broken crank cases of engines or the like.

Another object is to provide a novel projectile comprising essentially, a projectile-shaped chamber containing a quantity of compressed oxygen, or oxygen releasing substance such as chlorate of potassium which decomposes upon application of heat to release free oxygen, said chamber being disposed adjacent the projectile nose, whereby when the projectile strikes the object, the intense heat developed by reason of the impact and resulting deformation of the projectile nose melts the front end of the oxygen chamber, releasing the oxygen which combines immediately with the material of the object causing the projectile to blow its way into or through the object; and thus the projectile will penetrate the object not only due to the initial firing force of its discharge, but also due to the combined force of the liberated oxygen, the final action of said released oxygen, after the projectile has penetrated nearly through the object after initial impact serving to blow hot metal through and beyond the object.

Another object of the invention is to provide a projectile of the above type, having at its nose an additional chamber separated by a wall from the oxygen chamber, the additional chamber being disposed between the nose and oxygen chamber, and containing a material such as "Thermit" which is the trade name for a mixture of finely divided aluminum and iron oxide, which mixture upon reaction produces about one-half its weight of superheated molten steel and about one-half of molten alumina slag, both at a temperature of 5000° F. Thus the "Thermit" will initially be ignited, upon impact of the projectile, at a temperature much lower than that required for melting steel; and thus the heat generated by the impact of the projectile on the object will first ignite the "Thermit" charge, which in turn will generate an intense heat of about 5000° F. serving to melt the nose of the projectile and the wall which separates the "Thermit" chamber from the oxygen chamber, thereby insuring that the oxygen will be released, particularly when the projectile

5 does not have a sufficiently high velocity to cause a high temperature to be developed at the nose upon impact, or in event the impact should occur under water such as in case the projectile is in the form of, or used as, a torpedo.

10 A further object of the invention is to provide a projectile of the above type provided with separate oxygen and "Thermit" chambers, means being provided for positively igniting the "Thermit" charge upon impact, said means comprising a plunger disposed in the nose of the projectile and extending beyond the tip thereof, said plunger operating a combustion cap in the "Thermit" chamber at the moment the nose of the projectile strikes the object, the ignited "Thermit" charge serving to melt the nose of the projectile and the wall separating the "Thermit" chamber from the oxygen chamber so that the released oxygen will combine with the molten steel of the nose of the projectile and adjacent parts of the object, allowing the projectile to enter or pierce the object in the manner previously described, the use of the plunger being particularly useful in event the projectile is intended to impact an object under water, or under other conditions tending to lower the temperature caused by the impact.

15 I will explain the invention with reference to the accompanying drawing which illustrates several practical embodiments thereof, to enable others familiar with the art to adopt and use the same; and will summarize in the claims, the novel features of construction, and novel combinations of parts, for which protection is desired.

In said drawing:

20 Fig. 1 is a longitudinal section through one form of projectile constructed in accordance with my invention.

Fig. 2 is a longitudinal section through a modified form thereof.

25 Fig. 3 is a longitudinal section through a further modification thereof.

In Fig. 1, the projectile consists of a cylindrical shell 1 having a pointed nose 2, and having its rear end internally threaded as at 3 to receive a plate 4 which is externally threaded as at 5 to engage the threads 3. To facilitate filling the chamber formed by the shell and plate 5, a plug 6 threaded into the shell 1 adjacent nose 2, and/or a plug 7 is threaded into the plate 4. When the plugs 6 or 7 are removed the chamber may be filled with a compressed oxygen 23, or other substance or compound which will release oxygen, when heated, to combine with the hot molten metal of the projectile nose 2 and with the material of the object as rapidly as possible, such

as chlorate of potassium which decomposes upon application of heat to release free oxygen. However, the use of oxygen compressed in a gaseous state up to 2000 pounds per square inch is preferable since same furnishes a maximum amount of oxygen, when released, than any other substance or compound.

When the projectile is discharged from the gun and strikes an object, the intense heat caused by the impact at high velocity and the deformation of nose 2, melts the front end of shell 1, thereby releasing the oxygen which combines with the molten metal of the nose and the material of the adjacent parts of the object, thus allowing the projectile to penetrate the object by the initial force imparted to it when fired, augmented by the explosive force of the compressed oxygen, the action of the oxygen after the projectile has partly penetrated through the object being to blow the hot metal through and beyond the object, thus facilitating the progress of the projectile in boring its way through the object. Moreover, upon penetration, the sprayed molten metal will cause severe concussion in event the hot metal comes in contact with oil such as derived from oil tanks or bunkers, or from engine crank cases or the like.

In Fig. 2 a modification is shown in which the projectile consists of a shell 10 of cylindrical shape internally threaded at its rear end, as at 11, to receive plate 12 which is externally threaded as at 13 to engage threads 11, the plate 12 also having a filling plug 14 similar to plug 7 shown in Fig. 1. The forward end of projectile is contracted into the usual shape but the forward tip of shell 10 is blunt, as at 15, and an axial threaded bore 16 is provided therein terminating in an axial recess 17 separated from the main portion of shell 10 by a solid wall 18. A pointed cap 19, forming the nose of the shell, and having a threaded shank 20, is screwed into the threaded bore 16 of the shell, said threaded shank 20 and cap 19 having an axial recess 21 forming a continuation of the recess 17 of shell 10. The forward chamber, formed by the recesses 21 and 17, is filled with a material 22 such as "Thermit" which is the trade name for a mixture of finely divided aluminum and iron oxide which upon reaction produces about one-half its weight of superheated molten steel and one-half molten alumina slag both at a temperature of 5000° F., which "Thermit" will be ignited at a temperature much lower than that required for melting steel, while the larger chamber at the rear portion of shell 10 is filled with compressed oxygen 23 or other oxygen releasing substance or compound as previously described, which oxygen releasing material is inserted into the shell 10 either through the plug 14 in the plate 12 or through a threaded plug 24 in the side of shell 10 adjacent but in rear of the partition 18.

The operation of the shell shown in Fig. 2 is in general similar to that above described in connection with Fig. 1. Upon impact of the shell with the object, the nose 19 is deformed and the heat generated by impact and deformation ignites the "Thermit" 22 which generates a heat of about 5000° F. The use of the "Thermit" is to insure the release of the oxygen especially in event the projectile does not have a high velocity necessary to cause high temperature upon impact; or in event the impact is intended to occur under water, such as in the case of a torpedo-type projectile; or in event the impact is effected under conditions tending to lower

the temperature caused by the impact. This intense heat melts the cap 19 and the forward end of the shell 10, also the partition 18 between the "Thermit" chamber and the oxygen chamber, thereby releasing the oxygen 23 which combines with the material of the object, blowing its way into or through the object. Thus the projectile will effect penetration by the force imparted initially to it when it was fired from the gun, augmented by the expansive force of the compressed oxygen, the action of which oxygen, after the projectile has penetrated partly through the object, being to blow hot metal entirely through and beyond the object. The sprayed molten metal moreover will cause severe concussion when contacting any oil.

In the modification shown in Fig. 3, the projectile is in general similar to that shown and described in connection with Fig. 2, and like parts are similarly lettered. In this modification however a plunger and combustion cap is used to positively ignite the "Thermit" 22 upon impact in event the projectile is intended to impact under water or under conditions tending to lower the temperature caused by the impact. In this modification, the cap 19 is provided with a reduced axial bore 25 communicating with the bore 21, and a plunger 26 extends through bore 25 beyond the nose of the projectile and also extends rearwardly through recess 21 and into the "Thermit" charge in recess 17, the inner end of plunger 26 contacting a combustion cap 27 disposed axially of the recess 17 and seating against the wall 18 of the shell 10. Thus when the projectile contacts the object, the "Thermit" will be positively ignited, generating a heat of about 5000° F., which heat augmented by that due to the impact melts the forward end of the shell 10 and the partition 18 between the "Thermit" chamber and oxygen chamber. The released oxygen then combines with the material of the object and blows its way into or through it by the force imparted to it when fired plus the explosive force of the compressed oxygen, the action of the oxygen after the shell has penetrated partly through the object, being to blow hot metal entirely through and beyond the object.

By the above construction I provide a projectile which serves several purposes, namely, to burn its way through the object, to spray hot metal on partial penetration, and to cause severe concussion when the shell sprays the hot metal and the oxygen in the presence of oil, such as that which may be spread from broken oil tanks or from crank cases of engines or the like.

I do not limit my invention to the exact forms shown in the drawing, for obviously changes may be made thereon within the scope of the claims. Moreover, my invention might be used in connection with projectiles having explosive actions, but presumably the penetrating ability would be somewhat altered if the projectile was of the type adapted to explode upon impact. However, the blowing through of the hot steel according to my invention after penetration, will have fully as much destructive effect as if the projectile carried an explosive charge, especially if the released sprayed oxygen should contact free oily substance, as above stated.

I claim:

1. A projectile consisting of a hollow metallic shell having a pointed nose and a closed rear end; a partition wall within the shell dividing the interior thereof into front and rear chambers; a high oxygen releasing substance filling the rear

chamber adapted upon impact with a target to combine under heat generated by impact with the combustible substances of the target; and a substance filling the front chamber having a substantially lower ignition point than the melting point of steel and adapted when burning to develop intense heat.

2. In a projectile as set forth in claim 1, said substance in the front chamber comprising a mixture including finely divided aluminum and iron oxide.

3. In a projectile as set forth in claim 1, said oxygen releasing substance comprising compressed oxygen.

4. In a projectile as set forth in claim 1, said oxygen releasing substance comprising chlorate of potassium.

5. In a projectile as set forth in claim 1, the front end of the shell being blunt and having a recess; and a cap having a pointed nose removably mounted on the blunt end of the shell permitting, when removed, access to the recess, said cap having a second recess communicating with the first mentioned recess; the two said recesses together forming the front chamber.

6. A projectile consisting of a hollow metallic shell having a pointed nose and a closed rear end; a partition wall within the shell dividing the interior thereof into front and rear chambers; a high oxygen releasing substance filling the rear chamber and adapted upon impact with a target to combine under heat generated by the impact with the combustible substances of the target; a substance filling the front chamber having a substantially lower ignition point than the melting point of steel and adapted when burning to develop intense heat; and means for positively igniting the substance in the front chamber by impact.

7. In a projectile as set forth in claim 6, said igniting means comprising a plunger extending through a bore in the nose and projecting beyond the tip thereof and terminating within the front chamber; and a detonator within the front cham-

ber seating against said wall and being engaged by said plunger.

8. In a projectile as set forth in claim 6, said substance in the first chamber comprising "Thermit."

9. A projectile consisting of a hollow metallic shell having a pointed nose and a closed rear end; a partition wall within the shell dividing the interior thereof into front and rear chambers; a high oxygen releasing substance filling the rear chamber; a substance filling the front chamber having a substantially lower ignition point than the melting point of steel and adapted when burning to develop intense heat; and means for positively igniting the substance in the front chamber by impact, said oxygen releasing substance comprising compressed oxygen.

10. A projectile consisting of a hollow metallic cylindrical shell having a blunt nose and having a closed rear end forming a chamber; a high oxygen releasing substance filling said chamber and adapted upon impact with a target to combine under heat generated by the impact with the combustible substances of the target; the blunt end of the shell having a threaded recess; a cap having a pointed nose and having a threaded shank threaded into said recess, said cap permitting, when removed, access to the recess, said cap having a second recess communicating with the first mentioned recess; the two said recesses together forming a second chamber; and a substance having a substantially lower ignition point than the melting point of steel and adapted when burning to develop intense heat, filling the second chamber.

11. In a projectile as set forth in claim 10, a plunger extending through a bore in the cap and projecting beyond the tip thereof and terminating within the second chamber; and a detonator within the front chamber seating against said inner end of the first recess and being engaged by said plunger.

CLARENCE W. GALEN.
